UNITED STATES PATENT OFFICE.

WILLIAM E. WINE, OF TOLEDO, OHIO.

SLOPE SHEET FOR FREIGHT CARS.

Application filed March 13, 1928 Serial No. 261 235.

My invention relates to new and useful improvements in freight cars, and more particularly to the arrangement and construction of the slope sheets.

5 As is well known to those skilled in the art, a plurality of slope sheets are used forming a part of the bottom of coal carrying cars, which sheets extend down into the hoppers so that when the coal is loaded into the car, it 10 will run down the slope sheets and first fill up the several hoppers.

It is desirable in building freight cars of the maximum capacity type, to provide in the slope sheets a clearance for certain of the 15 wheels, one of the reasons being that in a present day method of switching freight cars there is what is known in the art as a "vertical curve" in the track, that is, a track is laid having sharp upward and downward curve, 20 so that the freight cars can be run up on this vertical curve and then unhooked and the car or cars will run by gravity down the curve and incline, and a switchman will then switch the car on the desired track or siding. This 25 manner of switching the cars does away with a number of switch engines, as the one engine can simply push the cars over the vertical curve and incline and let them be switched after they run down the incline to the desired 30 switch.

Due to this steep, short elevation or vertical curve, as it is called, the trucks must be capable of a vertical tilting movement, and naturally clearance must be provided in the 35 slope sheets for the tilting of two of the wheels of each truck.

One of the present objects of the invention, therefore, is to provide the slope sheets with a crown, pocket or other raised portion that 40 will provide the proper clearance for the truck wheels. At the same time, the crown must be so designed that it will not hinder the flow of coal down the hopper sheets, but on the other hand will divide the stream of 45 coal and assist in guiding it in its passage to the hoppers.

Still another object of the invention is to provide the hopper sheets with a crown, which crown is either formed integral with 50 the hopper sheet, or is a separate stamping that may be quickly fitted into a special opening provided in the hopper sheet.

Still another object of the invention is to provide the hopper sheet with either an integral or quickly attachable crown or pocket so constructed that it will divide the flow of

coal as it flows down the slope sheet and guide it in its flow and at the same time will be so constructed that it will add but little resistance to the flow of the coal to the hopper. 60

Still another object of the invention is to provide a freight car having these specially formed slope sheets therein, to allow for a vertical tilting of the truck and its wheels, and 65 at the same time will not hinder the flow of coal but will help direct it to properly fill up the hoppers.

Still another object of the invention is to 70 design and construct these slope sheets that they may be cut from stock, placed in presses with a special die to form the crown integral with the sheet, or the sheet may be cut with an opening and the crown formed in a different press and then riveted in place. 75

With these and other objects in view the invention consists in certain new and novel arrangements and combination of parts as will be hereinafter more fully described and 80 pointed out in the claims.

Referring now to the drawings, showing a preferred embodiment and a modification of the invention.

Fig. 1 is a fragmentary side elevation of a 85 full capacity car of the "Wine type", the dotted lines over the wheels showing the crown or pocket in the slope sheet.

Fig. 2 is a fragmentary top plan showing the position of the slope sheets and the position of the pockets therein. 90

Fig. 3 is an enlarged fragmentary sectional view showing the arrangement and position of one of the pockets.

Fig. 4 is a top plan view of the crown when the same is formed in a separate piece of 95 metal rather than pressed up in the slope sheet.

Fig. 5 is a side elevation thereof.

Fig. 6 is a sectional view taken on line 6-6 of Fig. 5. 100

Fig. 7 is a sectional view taken on the line 7-7 of Fig. 5.

Fig. 8 is a sectional view taken on the line 8-8 of Fig. 5.

Fig. 9 is a top plan view of a slope sheet 105 showing the cut out portion for the reception of the crown.

Fig. 10 is a fragmentary detail of one corner of the slope sheet.

Fig. 11 is a sectional view taken on line 110 11-11 of Fig. 10.

Fig. 12 is a top plan view of a modified

form of slope sheet showing the crown as pressed right from the slope sheet, and

Fig. 13 is a fragmentary sectional view taken on line 13—13 of Fig. 12.

5 Referring now more specifically to the several views, and to Figs. 1 and 2 in particular, there is fragmentarily shown an end of a freight car of the "Wine type", and in this view may be seen the side sheet 1, the 10 end side sheet 2, of special formation, and the side sill 3 which is also of special formation.

These several special parts, however, do 15 not form any part of the present invention, but are the subject matter of other patents granted to me and pending applications— Patent 1,661,863, dated March 6, 1928, and pending applications 250,781, filed January 31, 1928, 193,612, filed May 23, 1927, and 20 146,977, filed November 8, 1926.

In Fig. 1 there may also be seen the hopper 4, together with the hopper door hook 5. While the slope sheets 6 shown in dotted lines may be seen extending from the end of the 25 car down to the hopper.

In dotted lines are shown the wheels 7 and the pocket or crown 8, which crown provides sufficient clearance for any vertical movement of the wheel 7, as well as swinging 30 movement of the truck and wheels.

Referring now for the moment to Fig. 2, which is a fragmentary top plan of the end of the car, there will also be seen the top rails 9 showing the manner in which they 35 taper at 10 near the end of the car to provide clearance for the ladder.

It will be understood, however, at the outset, that the present invention may be used with any type of hopper car.

40 In Fig. 2 there may be seen the two slope sheets 6 connected to the center sill 11, which sheets are cut along their inner adjacent edges so that they may be properly fastened to the said center sill.

45 The outer edges of the slope sheets 6 are riveted to the side of the car and to the side sills, and extend downwardly to the hoppers 4, as may be readily understood.

Taking up now the gist of the invention, 50 that is, the special formation of the hopper sheet and its pocket, and referring to Figs. 3 to 9 inclusive, it will be seen that the slope sheet 6 is slightly wider at its end 12 than it is at its end 13, the metal being cut away 55 on its one side as at 14, and its other side as at 15. Also, there is a special flange 16 on its one side which is turned up so that it may be readily riveted to the side sill, and one of the corners 17 is slightly cut away to fit 60 about a side stake.

The general outline, however, of this slope sheet, of course, can be varied to suit the conditions present, and the outline shown is one that is adapted to fit the car shown in 65 the present drawing.

Still referring to Fig. 9, it will be seen that there is an opening 18 provided in the sheet having its one edge or wall 19 parallel with the end 13. The side walls 20 of this opening extend slightly toward each other to the 70 points 21, where they are cut abruptly to the apex 22. A line of rivet holes 23 is formed around this opening 18 so that the crown formation 8 as clearly shown in Fig. 4, may be securely riveted to the slope sheet. 75

Referring now especially to Figs. 4 to 8 inclusive, there may be seen the crown and the manner of forming the same, which will now be described. A sheet of metal is pressed or drawn to form a crown and so cut that there will be a flange 24 around the periphery thereof, which flange is adapted to fit on the underside of the slope sheet 6 and about the outline edge of the opening 18. This flange may be riveted tightly in position, there being a line of rivet holes 25 that will align with the rivet holes 23. In making this crown 8, it will be seen that the outline of the inner edges of flange 24 correspond with the outline of the opening 18, so that when the crown is placed within the opening 18 and riveted thereto, the vertical walls of the crown will just fit within the walls of the opening 18. 90

Referring now to Fig. 4, it will be seen that at one end 26 of the crown 8 there is a central rib 27, extending slightly above the upper surface walls or top 28 of the crown, which rib 27 dies out or merges as at 29, at the rear wall 30 of the crown. 95

When the crown is in position, as shown in Fig. 3, it will be seen that the top portion thereof extends for a short distance about parallel with the side sill and then drops abruptly to the point where it is fastened to the slope sheet. 100

In Fig. 5 there is shown the contour of the crown, when the same is lying flat, but it must be remembered that when it is in position it is disposed at an angle, because it is secured to the slope sheet which of course is angularly disposed. 105

In Figs. 8, 7 and 6, there are shown the cross sections of the crown and it will be noted that the crown at its front end has the sloping walls 28 (top) rather steeply inclined, while the vertical walls 31 are relatively short. In Fig. 7, however, the vertical side walls 31 have increased in height, and the top walls 28 are less abrupt. 110

In Fig. 6, that is, near the rear end of the crown, the vertical walls 31 are again decreased in height, and the top walls 28 are merged and form a horizontal surface. 115

By forming the opening 18 in the sheet and riveting the crown up, within the opening, it will be seen that space is provided for the swinging of the truck and also for greater vertical movement of the wheels, than is customary with the freight cars now in general service. Furthermore, as the coal slides 120 125 130

down the hopper-sheet, there is but little obstruction to the flow of the coal and in fact it will strike against the forward end and top walls of the crown and slide off to the sides 5 and downwardly into the hoppers.

In this way, what might otherwise be an obstruction to the passage of the coal, will in this instance, assist the coal in its flow and as the hoppers are emptied, the coal will slide off 10 the top and down the sides of this crown and not be retarded when the hoppers are being emptied.

In Figs. 12 and 13 I have shown a slightly modified form, that is, rather than making the 15 crown from a separate sheet of metal, I form the crown integral with the hopper sheet 6'.

Of course, allowance will have to be made in the size of the sheet so that the metal can be drawn up into the crown, and possibly a 20 heavier stamp press will have to be used, but from a manufacturing standpoint, there will be certain advantages gained, such as by cutting out the cost of the rivet and for the labor in applying the rivets.

25 It will be understood that the general construction of the slope sheet 6' will be similar to the slope sheet 6, and that the outline of the crown 8' is identical with the crown 8, but of course there will be no flange corresponding 30 to the flange 24 and no rivet holes as this crown is just to be pressed bodily right in the slope sheet 6'.

As heretofore mentioned, the general outline of the slope sheets of both forms might be 35 changed to be accommodated by different forms of hopper cars, and therefore, the general outline of the plate is to be merely considered as illustrative.

40 The size of the crown might be changed or variations might be made in the outline of the crown proper, although I have found that the general shape and arrangement of the different contours throughout the length and width of the crown, as shown, is practical and will 45 perform the functions desired.

I am aware that it is old to simply provide 50 a pocket in a slope sheet, as is shown in the patent to Schoen, No. 584,709 of 1897, the pocket in this instance simply being shown to provide the pocket for the wheels of the truck, but no provision is made in this arrangement for dividing the coal or assisting the coal in its flow from the crown, the pocket being shown as simply an arcuate plate and 55 struck from a center at a distance from the car.

From the foregoing it will be seen that I have provided slope sheets for a hopper car, wherein provision is made for the swinging 60 of the trucks and a tilting of the trucks, and at the same time, have so constructed the means that they will not hinder the coal in its flow to the hopper.

Also, I have shown how the pocket may be 65 formed integral with the slope sheet or how

the crown might be made of a separate sheet and riveted in place. Although not shown, it will of course be understood that the slope sheets at both ends of the car will be constructed in a like manner. 70

In a companion case I have shown a still further form of construction of the crown, new Serial Number 264,605, filed March 26, 1928.

Having thus described my invention, what 75 I claim as new and desire to secure by Letters Patent is:—

1. A slope sheet having a crown formed therein, the side walls of the crown being vertical, and the top surface of the crown 80 sloping towards the side walls, the front edge of the crown having sloping top walls and the rear end of the crown having its top wall horizontal throughout its width.

2. A slope sheet for coal cars having an 85 opening formed therein and a cover over the opening in the form of a crown being pointed at its forward end, the said crown having vertical side walls and the top surface of the crown sloping towards the side walls at the 90 forward end of the crown and the top surface of the crown flat at its rear end.

3. A slope sheet for a freight car having 95 a crown therein, the forward end of the crown extending to a point and the rear end of the crown being substantially parallel with the end of the sheet, the said crown having vertical side walls and the top of the crown at its forward end merging with a central rib, the rib dying out as it approaches 100 the rear of the crown and the top surface of the rear of the crown being flat.

4. A slope sheet for freight cars having an 105 opening cut therein, a crown having a flange and the flange adapted to be riveted around the edges of the opening, the said crown being pointed at its forward end and blunt at its rear end, the crown provided with vertical side walls that are increasing in height to about the center of the length of the crown, 110 the forward end of the crown having sharp sloping top walls and a rib located centrally of the top wall and extending part way throughout the length of the crown and the top walls flattening as they approach the rear 115 of the crown and substantially flat near the rear end of the crown.

5. A crown for a slope sheet, the crown comprising a single piece of metal and having a flange about its periphery, the crown 120 tapering from its rear end to its front end, vertical side walls, top walls merging with the side walls and a center rib extending part way throughout the length of the crown and the top walls flattening out as they approach 125 the rear of the crown.

6. A slope sheet of irregular shape for freight cars and the said slope sheet provided with a turned up flange near its rear end, the said slope sheet provided with a substantially 130

central cut-out portion, a crown provided with a flange and adapted to be riveted about said opening, said crown being pointed at its forward end and blunt at its rear end, a central rib on the upper surface of the crown and the forward top walls of the crown sloping sharply and flattening out as they approach the uppermost surface of the crown and the sloping top wall merging into a horizontal plane near the rear end of the crown.

7. A slope sheet for freight cars provided with a cut-out portion and a metal crown adapted to be secured over the said cut-out portion to form a pocket for the reception of the car wheel, said crown being wedge shape and sloping top walls at its forward end and a flat surface at its rear end.

8. A freight car having slope sheets at its opposite ends, each of said slope sheets provided with a crown portion therein and adapted to provide vertical and lateral swinging of the wheels, said crown being wedge

shape and the point of the wedge extending towards the adjacent ends of the car, the forward end of the crown having sharply inclined top walls and merging into a flat surface as these walls approach the rear of the crown.

9. A freight car provided with the usual slope sheets, crowned pockets in each of the slope sheets to provide clearance for the wheels, the said crowns being pointed at their one end and the apex of the crowns pointing towards the adjacent ends of the car, said crowns having vertical side walls, sharply pointed top walls at their one end and a rib extending from the apex and rearwardly of the crown and said rib and sharply inclined top walls merging into a flat surface as they approach the rear end of the crown.

In testimony whereof I affix my signature.

WILLIAM E. WINE.
